HATCH COVER AND MEANS FOR LOCKING
THE SAMEWilfred A. Beauchamp, Chicago, Ill., assignor to
The Youngstown Steel Door Company, Cleve-
land, Ohio, a corporation of Ohio

Application September 25, 1944, Serial No. 555,730

12 Claims. (Cl. 105—377)

1

This invention relates to hatch covers and means for locking the same.

It is an object of this invention to provide covers, particularly for covered railway hopper cars, and means for locking the covers which are so constructed that one man can close and lock the covers.

A further object is to provide hatch covers and locking means therefor which shall eliminate or substantially reduce distortion of the locking means.

A further object is to provide hatch covers and locking means therefor which shall eliminate practically all projection of the locking means above the covers.

A further object is to provide hatch covers having locking members so constructed and arranged as to serve as handles for the covers.

Other objects of the invention will become clear as the description thereof proceeds.

In the drawings forming part of this specification:

Fig. 1 is a partial plan view of a covered railway hopper car embodying the instant invention.

Fig. 2 is a vertical section taken on line 2—2 of Fig. 1, parts being broken away, showing a hatch cover in locked position.

Fig. 3 is a partial vertical section corresponding to Fig. 2 showing the cover closed and the locking member reeleased from its detent.

Fig. 4 is a partial vertical section corresponding to Fig. 2 showing the cover closed and the locking member disengaged from its detent and in position to serve as a handle for raising the cover.

Fig. 5 is a partial vertical section corresponding to Fig. 2 showing the cover partially open and the locking member out of engagement with its detent.

Fig. 6 is a vertical section taken on line 6—6 of Fig. 1.

Fig. 7 is a vertical section taken on line 7—7 of Fig. 1.

Referring to the drawings which illustrate a preferred embodiment of the invention, the numeral 10 designates a portion of the side sheathing of one of the side walls of a covered railway hopper car. The sheathing 10 is secured in any desired manner to a side plate 11 to which the roof 12 of the car is also fastened. Formed in the roof are a plurality of hatches 13. Secured to the roof 12 around each hatch is a hatch frame 14 formed preferably of angle members as more clearly shown in Fig. 2 of the drawings. The running board for the roof is shown at 15.

A hatch cover 16 is pivotally secured to each

2

of the hatch frames 14 as indicated at 17 by means of bracket members 18. Each of the covers 16 is preferably formed of sheet metal which is turned downwardly to provide the peripheral flange 19. The peripheral flange of the hatch cover is spaced outwardly of the hatch frame 14 and carries an angle member 20 disposed in overlapping relationship with an angle member 21 fastened around the hatch frame in order to provide a seal for the hatch cover. It is to be understood, however, that any other form of seal may be utilized if desired or that the seal may be entirely omitted.

For the purpose of locking the hatch covers 16 upon the hatch frames the instant invention provides U-shaped locking means 22 the branches 23 and 24 of which are pivotally secured to the free end of the hatch covers by means of the brackets 25 and 26 fastened to the peripheral flange of the covers. From Figs. 2 to 6, inclusive, it will be observed that the brackets 25 and 26 project very little above the top of the covers. With particular reference to Fig. 4 of the drawings, it will be clear that the relationship between the locking means 22 and the brackets 25 and 26 is such that the locking means is capable of serving as a handle for raising the covers.

A bracket 27 is secured to each of the hatch frames 14. The bracket members 27 are substantially T-shaped, the flanges 28 and 29 thereof being secured as by means of rivets to the hatch frames and the stem 30 thereof extending outwardly. As appears more clearly from Figs. 2 to 5, inclusive, the stem 30 is formed so as to provide a detent 31, which is preferably cam-shaped, and which as hereinafter more specifically pointed out, cooperates with the U-shaped locking means 22 in order to lock the covers upon the hatch frames.

40 A shaft 32 extends across the hatch frames and is rotatably mounted in the stems 30 of the brackets 27 below the detent portions 31. A plurality of fingers 33 and 34 are fastened upon the shaft 32 so as to rotate therewith adjacent to each stem 30 of each of the bracket members 27. Rotation is imparted to the shaft 32 by means of a lever 35 fastened thereto. The lever is adapted to be locked by means of a device indicated generally by the reference numeral 36 fastened upon the roof 12. The lever locking means which is of a well-known construction permits locking of the lever in various positions thereof. For a more detailed showing of the lever locking means, attention is invited to applicant's co-pending ap-

lication, Serial No. 535,176, filed May 11, 1944, now Patent No. 2,433,084, Dec. 23, 1947.

In order to lock the hatch covers, they are swung to the closed position where they are supported upon the hatch frames 14. The U-shaped locking means 22 for the covers will assume the position illustrated in Fig. 3 of the drawings. The shaft 32 is then rotated by means of the lever 35 in clockwise direction as viewed in Fig. 3 of the drawings. During such rotation of the shaft, the fingers 33 and 34 will also rotate and the fingers 33 will engage the U-shaped locking means 22 forcing such locking means into locking engagement with the detents 31. The formation of such detents as cams and the provision of means for fastening the lever 35 in various positions thereof insures proper locking engagement of the covers even though wear of the locking means or the detents, or both, may occur. The lever is then locked by the device 36 preventing rotation of the shaft 35. The fingers 33 lie in front of the locking means 22 and prevent accidental release of the locking means from the detents.

In order to unlock the covers so that they may be swung to open position, the shaft 32 is rotated in opposite direction by means of the lever 35. Rotation is thus imparted to the fingers 33 and 34 and fingers 34 will engage the locking means 22 and release them from locking engagement with the detents 31. The U-shaped locking means 22 may then be swung upwardly about their pivots to the position shown in Fig. 4 where they may be grasped by the hand in order to swing the covers open.

It is clear from the foregoing that the covers may be closed and locked and unlocked and opened by one operator. As a result of the instant invention locking, unlocking and opening and closing of the covers by a single operator may be obtained even if the covers become distorted so that they do not properly close when supported upon the hatch frames. Such a condition is illustrated in Fig. 5 of the drawings. It merely becomes necessary in this event for the operator to step upon the hatch cover so as to move it in closing direction until the U-shaped locking means engages the detent 31. Such engagement will retain the hatch covers in this position whereupon the operator rotates the shaft 32 by means of the lever 35 to bring about engagement of the fingers 33 with the locking means and resulting locking engagement between the locking means and the detents.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. In a covered railway hopper car having a roof formed with a series of spaced hatches and hatch frames secured to said roof around said hatches, covers hingedly secured to said hatch frames, locking means pivotally fastened to the free ends of said covers, members secured to said hatch frames, said members having locking detents, a shaft rotatably supported by said members below said detents, a lever secured to said shaft for imparting rotation thereto, and a plurality of fingers secured to said shaft adjacent to said detents, said fingers lying on opposite sides of and being engageable with said locking means

when the latter are engaged with said detents, and means for locking said shaft against rotation.

2. In a covered railway hopper car having a roof formed with a series of spaced hatches and hatch frames secured to said roof around said hatches, covers hingedly secured to said hatch frames, locking means pivotally fastened to the free ends of said covers, locking detents secured to said frames, a shaft rotatably mounted below said detents, members secured to said shaft adjacent to each of said detents for rotation with said shaft, said locking means being engageable with said detents prior to the rotation of said shaft, means for rotating said shaft, said members engaging and swinging said locking members into locking engagement with said locking detents upon rotation of said shaft, whereby said series of covers may be closed and locked by one operator, and means for locking said shaft against rotation.

3. In a covered railway car, a roof, a series of spaced hatch frames on said roof, covers for said frames, locking means pivotally fastened to a margin of each of said covers, locking detents secured to said frames, a rotatably mounted shaft extending along said frames, members secured to said shaft adjacent to said detents for rotation with said shaft, said locking means being engageable with said detents to lock said covers upon said frames, said members being adapted to be positioned in front of said locking means upon rotation of said shaft to prevent disengagement of said locking means from said detents, a lever secured to said shaft in spaced relation to said detents for rotating said shaft, said lever being in a substantially horizontal position when said members are in front of said locking means, and means for locking said lever in said position.

4. In a covered railway car, a roof, a series of spaced hatch frames on said roof, covers for said frames, locking means pivotally fastened to a margin of each of said covers, locking detents secured to said frames, a rotatably mounted shaft extending along said frames, members secured to said shaft adjacent to said detents for rotation with said shaft, certain of said members being adapted to engage said locking means with said detents upon rotation of said shaft in one direction to lock said covers upon said frame, the other members being adapted to release said locking means from said detents upon rotation of said shaft in the opposite direction, a lever secured to said shaft in spaced relation to said detents for rotating said shaft, said lever being in a substantially horizontal position when said covers are locked upon said frame, and means for locking said lever in said position.

5. In a covered railway car, a roof, a series of spaced hatch frames on said roof, covers for said frames, locking means pivotally fastened to a margin of each of said covers, locking detents secured to said frames, a rotatably mounted shaft extending along said frames, members secured to said shaft adjacent to said detents for rotation with said shaft, said members being adapted to engage said locking means with said detent upon rotation of said shaft to lock said covers upon said frames, a lever secured to said shaft in spaced relation to said detents for rotating said shaft, said lever being in a substantially horizontal position when said covers are locked upon said frames, and means for locking said lever in said position.

6. In a covered railway car, a roof, a series of spaced hatch frames on said roof, covers for said frames, locking means pivotally fastened to a

margin of each of said covers, locking detents secured to said frames, a rotatably mounted shaft extending along said frames, members secured to said shaft adjacent to said detents for rotation with said shaft, said members being adapted to engage said locking means with said detents to lock said covers upon said frames, said members lying in front of said locking means to prevent disengagement thereof from said detents, a lever secured to said shaft in spaced relation to said detents for rotating said shaft, said lever being in a substantially horizontal position when said covers are locked upon said frames, and means for locking said lever in said position.

7. In a covered railway car, a roof, a series of spaced hatch frames on said roof, covers for said frames, locking means pivotally fastened to a margin of each of said covers, locking detents secured to said frames, a rotatably mounted shaft extending along said frames, members secured to said shaft adjacent to said detents for rotation with said shaft, said members being adapted to engage said locking means with said detent upon rotation of said shaft to lock said covers upon said frames, a lever secured to said shaft in spaced relation to said detents for rotating said shaft, said lever being in a substantially horizontal position when said covers are locked upon said frames, and means for locking said lever in said position, said locking means constituting handles for said covers when released from said detents.

8. In a covered railway car, a roof, a series of spaced hatch frames on said roof, covers for said frames, locking means pivotally fastened to a margin of each of said covers, cam-shaped locking detents secured to said frames, a rotatably mounted shaft extending along said frames, members secured to said shaft adjacent to said cam-shaped detents for rotation with said shaft, said members being adapted to engage said locking means with said cam-shaped detents upon rotation of said shaft to lock said covers upon said frames, a lever secured to said shaft in spaced relation to said detents for rotating said shaft, said lever being in a substantially horizontal position when said covers are locked upon said frames, and means for locking said lever in said position.

9. In a covered railway car, a roof, a series of spaced hatch frames on said roof, covers for said frames, U-shaped locking means pivotally fastened to a margin of each of said covers, cam-shaped locking detents secured to said frames, a rotatably mounted shaft extending along said frames, members secured to said shaft adjacent to said cam-shaped detents for rotation with said shaft, said members being adapted to engage said locking U-shaped means with said cam-shaped detents upon rotation of said shaft to lock said covers upon said frames, a lever secured to said shaft in spaced relation to said detents for rotating said shaft, said lever being in a substantially horizontal position when said covers are locked upon said frames, and means for locking said lever in said position.

10. In a covered railway car, a roof, a series of spaced hatch frames on said roof, covers for said frames, locking means pivotally fastened to a margin of each of said covers, locking de-

tents secured to said frames, a rotatably mounted shaft extending along said frames, members secured to said shaft adjacent to said detents for rotation with said shaft, said locking means being engageable with said detents prior to the rotation of said shaft, a lever secured to said shaft in spaced relation to said detents for rotating said shaft, said members engaging and swinging said locking means into locking engagement with said detents upon rotation of said shaft, whereby said covers may be closed and locked by one operator, said lever being in a substantially horizontal position when said covers are locked, and means for locking said lever in said position.

15. 11. In a covered railway car, a roof, a series of spaced hatch frames on said roof, covers for said frames, locking means pivotally fastened to a margin of each of said covers, cam-shaped locking detents secured to said frames, a rotatably mounted shaft extending along said frames, members secured to said shaft adjacent to said

20 detents for rotation with said shaft, certain of said members being adapted to engage said locking means with said cam-shaped detents upon rotation of said shaft in one direction to lock said covers upon said frames, the other members being adapted to release said locking means from said cam-shaped detents upon rotation of said shaft in the opposite direction, a lever secured to said shaft in spaced relation to said detents for rotating said shaft, said lever being in a sub-

25 substantially horizontal position when said covers are locked, and means for locking said lever in position.

30 12. In a covered railway car, a roof, a series of spaced hatch frames on said roof, covers for said frames, U-shaped locking means pivotally fastened to a margin of each of said covers, cam-shaped locking detents secured to said frames, a rotatably mounted shaft extending along said frames, members secured to said shaft adjacent to said detents for rotation with said shaft, certain of said members being adapted to engage said U-shaped locking means with said cam-shaped detents upon rotation of said shaft in one direction to lock said covers upon said frames, the other members being adapted to release said U-shaped locking means from said cam-shaped detents upon rotation of said shaft in the opposite direction, a lever secured to said shaft in spaced relation to said detents for rotating said shaft, said lever being in a substantially horizontal position when said covers are locked, and means for locking said lever in position.

35 13. In a covered railway car, a roof, a series of spaced hatch frames on said roof, covers for said frames, locking means pivotally fastened to a margin of each of said covers, cam-shaped locking detents secured to said frames, a rotatably mounted shaft extending along said frames, members secured to said shaft adjacent to said detents for rotation with said shaft, certain of said members being adapted to engage said cam-shaped detents upon rotation of said shaft in one direction to lock said covers upon said frames, the other members being adapted to

40 release said cam-shaped locking means from said cam-shaped detents upon rotation of said shaft in the opposite direction, a lever secured to said shaft in spaced relation to said detents for rotating said shaft, said lever being in a substantially horizontal position when said covers are locked, and means for locking said lever in position.

45 14. In a covered railway car, a roof, a series of spaced hatch frames on said roof, covers for said frames, locking means pivotally fastened to a margin of each of said covers, cam-shaped locking detents secured to said frames, a rotatably mounted shaft extending along said frames, members secured to said shaft adjacent to said detents for rotation with said shaft, certain of said members being adapted to engage said cam-shaped detents upon rotation of said shaft in one direction to lock said covers upon said frames, the other members being adapted to release said cam-shaped locking means from said cam-shaped detents upon rotation of said shaft in the opposite direction, a lever secured to said shaft in spaced relation to said detents for rotating said shaft, said lever being in a substantially horizontal position when said covers are locked, and means for locking said lever in position.

50 15. In a covered railway car, a roof, a series of spaced hatch frames on said roof, covers for said frames, locking means pivotally fastened to a margin of each of said covers, cam-shaped locking detents secured to said frames, a rotatably mounted shaft extending along said frames, members secured to said shaft adjacent to said detents for rotation with said shaft, certain of said members being adapted to engage said cam-shaped detents upon rotation of said shaft in one direction to lock said covers upon said frames, the other members being adapted to release said cam-shaped locking means from said cam-shaped detents upon rotation of said shaft in the opposite direction, a lever secured to said shaft in spaced relation to said detents for rotating said shaft, said lever being in a substantially horizontal position when said covers are locked, and means for locking said lever in position.
